UNITED STATES PATENT OFFICE

FRED GLAHE, OF CHICAGO, ILLINOIS, ASSIGNOR TO A. G. SPALDING & BROS., OF NEW YORK, N. Y., A CORPORATION OF NEW JERSEY

SHOULDER PAD

Application filed January 13, 1931. Serial No. 506,434.

The present invention relates to protective devices for use during the playing of games, such as football, hockey, etc., and embodies, more specifically, an improved shoulder pad having portions which are adapted to conform to the movements of the shoulder during play.

More specifically, the invention includes a shoulder pad, wherein elements are hinged upon an axis permitting them to telescope partially in the fashion of the armor plate of an armadillo when the shoulder is moved.

It is becoming more and more important, particularly in football, to protect, adequately, a player's body, at the same time not impeding the free movement thereof during play. Existing protective devices have utilized shoulder pads, wherein the elements are connected as a unitary pad but, when the arm is raised, the construction has been such that the pad strikes the neck and thus hampers the free action of the player. As it is extremely necessary that the arms and shoulders of a player be unimpeded, particularly for forward passing, existing shoulder pads have been found to be inadequate both in the degree of protection afforded and in the failure thereof to permit the free movement of the arms.

An object of the present invention is to provide a shoulder pad having portions which are mounted to turn about axes which permit the partial telescoping of such portions to enable them to conform to the movement of the player's arms during play.

A further object of the invention is to provide a shoulder pad of the above construction having means to protect the upper arm and shoulder of a player in all positions thereof, as well as to provide for the free and unimpeded movement of such arm at all times.

Further objects, not specifically enumerated above, will be apparent as the invention is described in greater detail in connection with the accompanying drawings, wherein:

Figure 1 is a plan view, partly broken away to illustrate the details of construction, showing a portion of a shoulder pad constructed in accordance with the present invention.

Figure 2 is a view in section, taken on line 2-2 of Figure 1, and looking in the direction of the arrows.

Figure 3 is a detail view in section, taken on line 3-3 of Figure 2, and looking in the direction of the arrows.

Referring to the above drawings, a pad 10 is formed with front and rear protective portions 11 which form a recess adapted to receive a player's neck to position the pad over a shoulder. Lacing 12 may be provided to secure the pad to a cooperating similarly formed pad and thus afford full protection for both shoulders. Intermediate the portions 11, a slit 13 is formed in the padding 16, thus relieving the stiffness of the pad and permitting the resulting strap portion 14 to move with respect to the rest of the pad. The above described pad is formed with a relatively stiff but flexible outer layer 15 of leather and an inner protective layer 16 of felt.

Along the side of the slit 13, adjacent the neck recess, a protective portion 17 is secured, as by stitching 18. The protective portion is formed of an outer layer 19 of stiff and relatively inflexible leather, being provided with an inner layer 20 of felt or other suitable cushioning substance. The protective portion 17 thus extends over the slit and the strip 14 and affords adequate protection for the top of the shoulder.

An intermediate protective portion 21 is secured to the strip 14 by stitches 22 and thus is adapted to swing about an axis passing through the ends of the slit 13 as indicated by the arrow 23. In this manner, the intermediate member 21 may swing outwardly in the direction indicated by the arrow 24 and, being under the portion 19, may thus extend the effective protecting ability of the device considerably. The first protective portion 19 is preferably formed of such radius that the intermediate member moves in the above described fashion without restriction and the strip 14 and member 21 may thus move either from a position wherein the slit 13 is closed to a position in the direction of arrow 24, wherein the arm is against the player's side.

Hinged upon the intermediate member is

a lower member 25 which is hingedly secured to the intermediate member 21 by means of a lacing 26 or other device. Both the intermediate and lower members are provided 5 with inner layers of felt or other protective material in a well known fashion and a loop 27 is preferably provided to receive the arm and thus cause the intermediate and lower members to move freely with the movements 10 of the arm. The radius of the surface forming the lower member 25 is so designed that it may freely move under the intermediate member 21 and thus permit the player's arm to be raised into any desired position with 15 minimum interference and resistance thereto to permit passing and other action to be fully and freely engaged in. A loop 28 may be provided to pass under the player's arm and is secured to the side portions 11 to maintain the 20 pad in proper position and it will thus be seen that the degree of protection afforded by the pad is not only increased over existing designs, but the freedom of movement of the player is likewise increased.

25 While the invention has been described with specific reference to the accompanying drawings, it is not to be limited, save as defined in the appended claims.

I claim as my invention:

30 1. A protective device having an upper protective flap secured thereto, an auxiliary intermediate protective flap hinged to the device and lying beneath the upper flap, and a lower protective flap hinged to the intermediate flap and adapted to telescope thereunder.

35 2. A protective member formed with a slit providing a strap movable with respect to the member, a protective flap rigidly secured 40 to the member along one side of the slit and overlying the slit and strap, and a protective flap secured to the strap and movable telescopically with respect to the first flap.

45 3. A protective member formed with a slit providing a strap movable with respect to the member, a protective flap rigidly secured to the member along one side of the slit and overlying the slit and strap, an intermediate protective flap secured to the strap and movable telescopically with respect to the first flap, and a lower flap hingedly secured to the intermediate flap.

50 4. A protective member formed with a slit providing a strap movable with respect to the member, a protective flap rigidly secured to the member along one side of the slit and overlying the slit and strap, an intermediate protective flap secured to the strap and movable telescopically with respect to the first flap, and a lower flap hingedly secured to the intermediate flap and telescopically movable thereunder.

55 5. A shoulder pad formed with a neck recess and a slit in the pad adjacent the recess to 60 form a strap, a protective flap rigidly secured

to the side of the slit adjacent the recess and extending over the slit and strap, a flap secured to the strap and telescopically movable under the first flap, and a lower flap 70 hinged to the second flap and telescopically movable thereunder.

This specification signed this 27th day of December, A. D. 1930.

FRED GLAHE.
